DESIGN FOR A CLOTHESLINE FASTENER

Austin W. Grose, Celoron, N. Y.

Application September 2, 1944, Serial No. 115,174

Term of patent 14 years

(Cl. D54—11)

To all whom it may concern:

Be it known that I, Austin W. Grose, a citizen of the United States, residing at Celoron, in the county of Chautauqua and State of New York, have invented a new, original, and ornamental Design for a Clothesline Fastener, of which the following is a specification, reference being had to the accompanying drawing, forming part thereof; and in which

Fig. 1 is a perspective view of a clothesline fastener, showing my new design; and

Fig. 2 is a front elevational view thereof.

Fig. 3 is a vertical sectional view, taken substantially on a line between the right side wall and the cam of Fig. 2, looking toward the left of the drawing.

I claim:

The ornamental design for a clothesline fastener, substantially as shown.

AUSTIN W. GROSE.
